UNITED STATES PATENT OFFICE.

CHARLES L. E. REBERT, OF LOS ANGELES, CALIFORNIA.

DETACHABLE AND REVERSIBLE CUFF FOR SHIRTS.

1,286,102.

Specification of Letters Patent. Patented Nov. 26, 1918.

Application filed January 7, 1918. Serial No. 210,615.

To all whom it may concern:

Be it known that I, CHARLES L. E. REBERT, a citizen of the United States, residing at Los Angeles, in the county of Los Angeles, State of California, have invented new and useful Improvements in Detachable and Reversible Cuffs for Shirts, of which the following is a specification.

This invention relates more specifically to 10 a detachable and reversible cuff securing means, of the type illustrated and described in my allowed application entitled Detachable shirt cuffs S. N. 176,861 filed June 25, 1917, and an object of my present invention 15 is to provide an improved cuff attaching means, whereby when the cuffs are secured to a shirt they will present the appearance of the usual form of attached cuffs.

The further object of my invention is to 20 provide a reversible and attachable soft cuff securing means which will firmly maintain the same in position on a shirt sleeve and which will also effectually conceal the attaching means from view.

25 I accomplish the above objects by means of the construction herein described and illustrated in the accompanying drawings in which:

Figure 1 is a perspective view of my improved cuff.

Fig. 2 is a perspective view of one of my amended cuffs in a folded position, parts being broken away to disclose the securing means.

35 Fig. 3 is a perspective view of the wristband of a shirt, parts being broken away to disclose cuff attaching means.

Fig. 4 is a side elevation of the outer end 40 of a shirt sleeve showing my cuff in place thereon, parts being in section to disclose attaching means.

Fig. 5 is a transverse section of my improved cuff taken on line 5-5 of Fig. 4 looking in the direction indicated by the arrows 45 thereon.

Referring more particularly to the drawings 5 designates a cuff preferably formed of soft wash fabrics provided adjacent each of its four corners with buttonholes 6, 7, 8 and 50 9 which are engaged by the cuff buttons 10 in the usual manner.

Cuff 5 is designed to be folded centrally

upon itself along line $a-a$, and is preferably formed of several plies of material to stiffen same, one longitudinally extending edge being provided with a pocket 11 which is preferably centrally disposed between the cuff ends. Pocket 11 extends only a short distance inwardly from the edge of the cuff as shown in Fig. 1 of the drawing, and each of its walls forming the pocket is provided with buttonholes 12 and 13.

Each shirt sleeve 15 is provided with a wristband 16 having the usual button holes 17 through which the cuff buttons 10 pass 65 when the cuff 5 is secured thereto. Secured to the inner face of wristband 16 and midway between its ends is a cuff attaching button 18, said button adapted to engage with one of the buttonholes 12 or 13 formed on 70 the cuff.

In assembling my cuff construction preparatory to attaching it to the wristband of a shirt, the cuff is first folded upon itself along line $a-a$, the folded cuff straddling 75 wristband as clearly shown in Fig. 4 of the drawings, the button 18 engaging one of the buttonholes 12 or 13 of the cuff. The ends of the cuff are then secured in the usual manner by the cuff buttons 10 which pass through 80 the buttonholes formed in the cuff and the button holes in the wristband.

It will be noted further that by forming a pocket 11 the button 18 formed on the inner face of the wrist when secured in one of 85 the buttonholes will not contact with the flesh of the wearer thereby causing discomfort. Furthermore, by straddling the cuff on the wristband the same will be firmly maintained in position and will effectually 90 conceal from view any vestige of the securing means.

When the cuff becomes soiled along its exposed edge it may be reversed, the wearer simply turning the cuff end to end and securing it in the manner as hereinbefore described, the cuff then presenting to all appearances that of a freshly laundered one.

What I claim is:

A detachable and reversible cuff for shirts, 100 the combination of a shirt sleeve with a wristband, a button secured to the inner face of said wristband substantially midway between its ends, a cuff comprising a substan-

tially rectangular body formed of a plurality of plies of fabric having buttonholes at approximately each of its corners, one longitudinally extending edge of said cuff being 5 provided with a pocket, the walls forming said pocket each being provided with a buttonhole, said buttonholes adapted to engage with said button on said wristband, whereby when the cuff is folded longitudinally upon

itself and straddling the shirt wristband the 10 cuff can be secured to the sleeves of the shirt and the attaching means concealed from view.

In witness that I claim the foregoing I have hereunto subscribed my name this 18th 15 day of December, 1917.

CHAS. L. E. REBERT.
